(57) **CLAIM**

The ornamental design for a calendar slide, as shown and described.

DESCRIPTION

FIG. 1 is perspective view of a first embodiment of a calendar slide according to this invention shown broken away to indicate indeterminate length;

FIG. 2 is an enlarged detail view of the eyelet and surrounding portion of the calendar slide of FIG. 6;

FIG. 3 is a front view of the calendar slide of FIG. 1; FIG. 4 is an end view of the calendar slide of FIG. 1; FIG. 5 is a back view of the calendar slide of FIG. 1; FIG. 6 is a top view of the calendar slide of FIG. 1;

FIG. 7 is a bottom view of the calendar slide of FIG. 1; FIG. 8 is a perspective view of a second embodiment of a calendar slide according to this invention shown broken away to indicate indeterminate length;

FIG. 9 is an enlarged detail view of the eyelet and surrounding portion of the calendar slide of FIG. 13;

FIG. 10 is a front view of the calendar slide of FIG. 8;

FIG. 11 is an end view of the calendar slide of FIG. 8;

FIG. 12 is a back view of the calendar slide of FIG. 8;

FIG. 13 is a top view of the calendar slide of FIG. 8;

FIG. 14 is a bottom view of the calendar slide of FIG. 8; FIG. 15 is a perspective view of a third embodiment of a calendar slide according to this invention shown broken away to indicate indeterminate length;

FIG. 16 is an enlarged detail view of an eyelet portion of the calendar slide of FIG. 20;

FIG. 17 is a front view of the calendar slide of FIG. 15;

FIG. 18 is an end view of the calendar slide of FIG. 15;

FIG. 19 is a back view of the calendar slide of FIG. 15;

FIG. 20 is a top view of the calendar slide of FIG. 15;

FIG. 21 is a bottom view of the calendar slide of FIG. 15; FIG. 22 is perspective view of a forth embodiment of a calendar slide according to this invention shown broken away to indicate indeterminate length;

FIG. 23 is an enlarged detail view of the eyelet and surrounding portion of the calendar slide of FIG. 27;

FIG. 24 is a front view of the calendar slide of FIG. 22;

FIG. 25 is an end view of the calendar slide of FIG. 22;

FIG. 26 is a back view of the calendar slide of FIG. 22;

FIG. 27 is a top view of the calendar slide of FIG. 22; and, FIG. 28 is a bottom view of the calendar slide of FIG. 22.
